UNITED STATES PATENT OFFICE

HAROLD W. MARTIN, OF NATICK, MASSACHUSETTS, ASSIGNOR, BY MESNE ASSIGNMENTS, TO AMERICAN SEAL-KAP CORPORATION, OF LONG ISLAND CITY, NEW YORK, A CORPORATION OF DELAWARE

BOTTLE CAP AND METHOD OF APPLYING THE SAME

Application filed December 28, 1927. Serial No. 243,157.

In Patent No. 1,668,349 of Ewald G. Baum, granted May 1, 1928, is disclosed a method of making paper articles, such, for example, as milk bottle caps in which portions composed of overlapping folds of a properly prepared paper are so compacted together that moisture is substantially without effect thereon to tend to open up the folds. While this treatment is very effective for the purpose, it is found that if sufficient force is applied to the folded portions the layers may be torn away from each other, loosening up the compacted fibrous structure so that moisture can have access thereto in a manner to impair to some extent the resistance of the article to being injured thereby.

In the case of milk bottle caps a certain amount of distortion of the outer margin of the pouring lip housing without permanent damage would be quite desirable and it is the primary object of this invention to produce such articles wherein such distortion may be effected without damage and while retaining substantially the full advantage incident to the general treatment set forth in the Baum patent hereinbefore mentioned.

To this end the excess material of the waxed paper instead of being gathered in tight overlapping folds is gathered to some extent at least in outwardly extending ribs and is heavily compacted in such condition. These ribs can be opened up by applying force in the proper direction thereto without causing any tearing apart of fibers which have been heavily compacted together into intimate contact. This makes possible the application of sufficient force on the caps to stretch their marginal edges over the pouring lip housing of the bottle and if desired to such an extent that the outer edge of the cap may be engaged tightly about and somewhat beneath the pouring lip and yet without causing such damage to the cap as might cause it to be less able to successfully withstand the action of moisture. By the engagement of the cap with the under side of the pouring lip where it is of smaller diameter, the tenacity with which the cap holds to the bottle is increased.

The ribs on the outer face of the cap are

useful also from the fact that they impart a distinctive appearance and feel to the hand, so different from that of the caps not so formed that when used in connection with milk bottles containing a special grade of milk only, such bottles may be readily distinguished from those bottles containing other grades of milk. The distinctive feel of the cap is of importance, due to the fact that deliveries of milk to customers are usually made during hours of darkness where mistakes might easily be made were distinctive appearance only relied upon. The added security of sealing by the more extensive and tighter engagement of the caps over and beneath the pouring lip housings make such caps particularly suitable for use in connection with the best grades of milk such as certified milk.

For a more complete understanding of this invention, reference may be had to the accompanying drawings showing a milk bottle cap constructed according to this invention and in which

Figures 1 and 2 are top and inverted plan views of one portion of a milk bottle cap before being applied to a bottle.

Figure 3 is an elevation partly broken away of the same.

Figures 4 and 5 are fragmentary sections showing successive stages in the application of a cap to a bottle.

Figure 6 is a detail section on line 6—6 of Figure 3.

Figure 7 is a view similar to a portion of Figure 6, but illustrating the stretching of the cap margin as it passes from the position of Figure 4 to that of Figure 5.

Referring to these figures, it will be seen that the cap comprises a central bore covering portion 1 which in its preferred form is upwardly arched. This bore covering portion is provided with a margin 2 arranged to seat on the usual internal annular ledge 3 of the milk bottle, as shown in Figures 4 and 5. If desired, and which is regarded as the preferred construction a reinforcing disk 4 may be superposed over the bore covering portion 1 and over the margin 2. Extending upwardly from the outer edge of the

portion 2 is an annular pouring lip housing 5 which is arranged to extend over the pouring lip 6 of the bottle. It will be noted from an inspection of Figures 4 and 5 that this pouring lip extends outwardly so that it is of larger diameter than the neck portion 7 of the bottle therebeneath and that the cap as made has its pouring lip housing 5 somewhat higher than the pouring lip above the ledge 3.

The cap may be formed, as described in the Baum patent hereinbefore referred to, from a flat blank of paper or cardboard, initially treated with wax, the flat blank being molded to form. In molding up the pouring lip housing the material of the blank must be gathered together, and as shown, a portion at least of this material is concentrated in radially extending ribs 10, which as shown extend from a position somewhat above the ledge-engaging portion 2 upwardly over the top of the pouring lip housing and down on its outer face to its extreme edge. This material is gathered, as shown in Figure 6, so as to present externally of the cap, the rounded radially arranged rib or bead portions 10 spaced by portions 11 of substantially uniform thickness and slightly arcuate, their centers of curvature being substantially the center of the cap. The inner face of the pouring lip housing presents a substantially smooth surface as at 12, there being opposite to the ribs 10, portions 14 and 15, which are folded into contact as at 16. The portions 11 are substantially non-stretchable, while the intervening portions 10 are stretchable and resilient. The cap during its molding operation and while the fibers of the paper are in soft swollen condition as by treatment with water is subjected to such heavy pressure that the pouring lip housing particularly on its outer face, and any other portions which may be desired, are reduced to a dense substantially horn-like structure as is set forth in the Baum patent hereinbefore referred to. The portions 14 and 15, however, are not compacted together into intimate contact so that when a stretching force is applied to the cap, these portions may separate from each other, opening up at 16 somewhat, as shown in Figure 7 in an exaggerated degree, without causing any substantial tearing apart of the compacted fibers of the paper which might result in exposing the loosened fibers to the action of moisture. Thus a certain amount of stretching and distortion may be applied to the cap without so damaging it as to make it subject to injury from moisture entering the fibers and tending to cause the cap margin to flare.

The cap as thus constructed, and preferably with the reinforcing disk in position, is initially placed and seated on the bottle as shown in Figure 4, the capping plunger

20 by which such seating may be effected being shown as raised somewhat above the cap in this figure for the sake of clarity. The pouring lip housing in this position extends above the top of the bottle pouring lip and its outer edge extends downwardly about the outer face of this lip. Pressure may then be exerted on the cap in a direction to roll outwardly the upper portion of the pouring lip housing to cause it to more nearly conform to the upper edge of the pouring lip, into the position shown in Figure 5, this pressure acting to stretch the outer margin of the housing about the pouring lip and then to roll it in under the pouring lip, the portions 14 and 15 of each of the ribs closing together more or less again after the initial stretching, which has been illustrated in connection with Figure 5, has permitted this portion of the cap to pass around the lip. The margin of the housing bears against the under side of the lip by its inherent resiliency, requiring no fastening or tying devices to hold it in firm engagement therewith.

The manner in which this pressure may be exerted may be seen from an inspection of Figure 4, in which the applying plunger is shown as provided with a central portion 21 for engagement with the central portion of the bore covering portion, an annular portion 22 which engages the cap above the ledge 3 and seats it firmly thereagainst, and an outwardly and upwardly curved marginal portion 23 which first engages against the inner side of the pouring lip housing adjacent its upper portion and, as the plunger continues to descend, effects a progressive pressure outwardly over the top of the pouring lip housing until it is firmly seated thereon as shown in dotted lines in Figure 5. This pressure produces a rolling effect on the pouring lip housing which causes its outer margin to move inwardly toward the neck portion of the bottle around and beneath the pouring lip into substantially the position shown in Figure 5. The capacity for stretching possessed by the pouring lip housing by virtue of its construction, permits such action to take place even though the lip be considerably misshapen, without opening up the compacted fibers in such a way as to permit moisture to gain access thereto, the cap in its finally seated position being inherently resistant to moisture and holding to the bottle with great tenacity.

Having thus described an embodiment of this invention and its manner of use, it should be evident that various changes and modifications might be made therein without departing from its spirit or scope as defined by the appended claims.

I claim:

1. A milk bottle cap shaped prior to attachment to the bottle and comprising a waxed paper disk formed up with a marginal

pouring lip housing, the outer wall of said housing having certain of its material gathered into folds presenting outwardly projecting ribs, the material of said housing including said ribs being compacted together into a dense horn-like structure highly resistant to moisture, said outer wall being stretchable by the opening up of said folds without substantial effect on said dense structure.

10 2. A bottle cap for application to a bottle having an internal annular ledge and a pouring lip above said ledge, said bottle cap having a bore covering portion for engagement with said ledge, and a pouring lip housing 15 above its bore covering portion, said housing being initially higher than said pouring lip above said ledge and having a resilient outer margin to permit said housing portion to be rolled down toward the top of said pouring 20 lip and its margin to pass down and inwardly under said lip.

3. A bottle cap for application to a bottle having an internal ledge and a pouring lip above said ledge, said bottle cap comprising a 25 waxed paper disk initially molded to present a bore covering portion for engagement with said ledge, and a pouring lip housing higher than said pouring lip, the material of said disk being gathered together over said lip 30 and compressed into a dense horn-like structure having outwardly projecting folds forming ribs extending to the outer edge of said housing, the material of said housing being yieldable by a partial opening of said 35 folds without injury to said horn-like structure to permit said pouring lip housing to be depressed against the top of said pouring lip and the margin of said pouring lip housing to spring under and contact with the 40 lower part of said pouring lip.

4. A bottle cap for application to a bottle having an internal annular ledge and a pouring lip above said ledge, said bottle cap having a bore covering portion for engagement 45 with said ledge, and a pouring lip housing, said housing being initially higher than said pouring lip and having a resilient outer margin comprising non-stretchable portions with intervening stretchable resilient portions to 50 permit said housing portion to be pressed down toward the top of the pouring lip, and its margin to pass down and inwardly under said lip.

5. The step in the method of applying a 55 bottle cap having a marginal pouring lip initially higher than the bottle pouring lip and having an outer margin comprising non-stretchable portion with intervening stretchable resilient portions which comprises applying a force to the inner and upper portion of said housing in a direction to roll said housing down over the top of said pouring lip and with the outer margin of said housing contracted in under said lip.

65 6. The step in the method of applying a

bottle cap having a marginal pouring lip initially higher than the bottle pouring lip and having a stretchable and contractible outer margin, which comprises applying a force to the inner and upper portion of said housing in a direction to roll said housing down over the top of said pouring lip and with the outer margin of said housing contracted in under said lip.

In testimony whereof I have affixed my 75 signature.

HAROLD W. MARTIN.
